UNITED STATES PATENT OFFICE.

BELVIN T. WILLISTON, OF SOMERVILLE, MASSACHUSETTS, ASSIGNOR TO MANNING MAXWELL AND MOORE, INC., OF NEW YORK, N. Y., A CORPORATION OF NEW JERSEY.

BOILER-FEEDING INJECTOR.

1,392,098.

Specification of Letters Patent. Patented Sept. 27, 1921.

Application filed August 12, 1919. Serial No. 317,023.

To all whom it may concern:

Be it known that I, BELVIN T. WILLISTON, citizen of the United States of America, and resident of Somerville, in the county of 5 Middlesex and State of Massachusetts, have invented new and useful Improvements in Boiler-Feeding Injectors, of which the following is a specification.

My invention relates to injectors and more 10 particularly to boiler feeding injectors of the type used on locomotives.

In boiler feeding and other injectors it has been customary to provide a plurality of valves to control the forcer nozzle, the lifter 15 nozzle, the water inlet, the over flow, etc., and to regulate the flow of water through the injector by operating a plurality of these valves conjunctively. This practice has involved more or less complicated mechanisms 20 and more or less inconvenience and difficulty in controlling the action of the injectors. An object of the present invention is to simplify the construction of injectors, to reduce the number of valves and other 25 parts and to correlate the various parts so that the flow of water may be regulated from maximum to minimum by means of a single valve.

Moreover, in injectors which are subjected 30 to low temperatures, as *e. g.* are locomotive injectors in cold weather, it is necessary to heat the water standing in the water supply hose or pipe leading to the injector when the injector is not in use in order to prevent 35 the water from freezing, and in the case of locomotives it is also desirable to heat the water in the tender in very cold weather. Another object of the present invention, therefore, is to overcome the difficulties in- 40 cident to injector systems, in which means is provided for heating the water in advance of the injector when the injector is idle, or which are provided with heating means of the unsatisfactory types heretofore pro- 45 posed, and to provide improved means for accomplishing this purpose which involves little if any additional mechanism and which may be controlled with ease and cer- tainty.

50 Furthermore, in boiler feeding injectors and other injectors where the control levers or handles must necessarily be located at a considerable distance from the valves which they control, (and in practically all injector systems this distance must be more or less

considerable), there is a pronounced tendency for the valves not to remain tightly seated due to the unavoidable lost motion in the trains of linkage connecting the control handles with the valves and also to the vibration which is particularly troublesome in locomotive injectors. In the case of the main steam valves of injectors this is particularly serious for the reason that the leakage of steam through the injector, together with the water resulting from the condensation of steam or overflow from the boiler or other source, rapidly wears the interior parts of the injectors, the flow of steam mixed with water cutting out the injector 60 almost as rapidly as would a sand blast. A still further object, therefore, is to maintain the steam valve, and if desired other of the valves, tightly seated when the injector is idle notwithstanding lost motion in the control linkage and notwithstanding excessive vibration.

Other objects will be apparent from the concrete embodiment of the invention illustrated in the accompanying drawings in 70 which—

Figure 1 is a right side elevation showing parts broken away;

Fig. 2 is a left side elevation showing parts broken away;

Fig. 3 is a rear elevation on an enlarged scale of a portion of the injector viewed from the right of Fig. 1, parts being sectioned; and

Fig. 4 is a section on line 4—4 of Fig. 3;

Fig. 5 is a fragmentary cross section to enlarged scale illustrating the steam inlet valve.

The particular embodiment of my invention chosen for the purpose of illustration 95 comprises in general a main casing C, a water inlet nipple W, a steam inlet S, a delivery nipple D, and an overflow nipple O. Within the casing C (Fig. 4) is provided a steam valve Vs, a water valve Vw, and intermediate overflow valve Vo', a final overflow valve Vo'', a forcer nozzle FN, a forcer tube FT, a lifter nozzle LN, a lifter tube LT, etc. An annunciation or tell-tale T of any suitable construction communicates with the 100 casing C at 26, whereby when the injector casing C at 26, whereby when the injector "breaks" steam will issue therefrom to indicate that the injector has ceased functioning.

The steam valve Vs is a double valve hav- 110

ing an upper portion 1 seating on a seat 2 and a lower portion 3 seating on a seat 4, the lower portion being mounted on the upper portion by a lost-motion connection comprising a pin 5 slidable in a spider 6 depending from the upper portion whereby the upper valve may be raised part way before the lower valve begins to open. The upper end of valve V_s is adapted to engage against face 10 25 (Fig. 4) when the valve is opened for a purpose hereinafter described.

The upper valve 1 of the double steam valve V_s and its seat 2 are provided with telescoping portions which prevent steam 15 from passing the valve until the valve has been opened a considerable amount; and in the specific embodiment of the invention illustrated in the drawings valve 1 is provided with a downwardly directed piston-20 like extension 22 fitting fairly closely into the opening in the valve seat but having sufficient freedom in said opening to permit the bleeding of steam thereby. The piston 22 extends downwardly to the plane 23 and the 25 spider 6 extends downwardly from the lower end of the piston to guide the valve and to support the lower valve 3. A groove 24 may be provided at the junction of the spider with the piston. When the valve V_s is lifted 30 a small and predetermined quantity of steam may bleed past the piston 22 until the latter is completely withdrawn from the opening in the valve seat 2.

The water valve V_w is also a double valve 35 comprising an upper portion 10 rotatably mounted by threads 11 and a lower portion 8 telescoping into the upper portion with a sliding fit. The lower valve 8 has a flange seating on seat 9 and this flange has four 40 openings 13 extending therethrough. The upper valve 10 has a flange seating on the flange of the lower portion 8 over the openings 13. The upper valve 10 is rotatably supported by threads 11 engaging an inter-45 nally threaded holder, said threads having such a high pitch that the valve may be opened by a single turn of the rod 12. The lower valve 8 rises with the upper valve if the pressure beneath the valve is greater 50 than above whereas if the pressure above is substantially greater than below the valve 8 remains seated when the valve 10 is raised thereby uncovering openings 13.

In a locomotive injector system the control 55 handles are located in the cab and consequently the control handles C_s C_w and C_o , for the steam, water and overflow valves respectively are connected to the respective valves through trains of linkage. The 60 handle C_s is connected to the steam valve V_s through the medium of a bowed rod 14, a member 15, and the rod 7 extending inside casing C. The member 15 is pivotally mounted on the casing by means of side 65 straps 16 pivoted at 16'. The handle C_w is

connected to the water valve through a series of shafts and universal joints 17 and 17'. The handle C_o is connected to the final overflow valve V_o'' through a similar series of shafts and universal joints 18 and 18'. 70

A feature of the invention consists in the combination of the bowed link 14 in the linkage connecting the steam valve with its control handle. This bowed link is made of steel having sufficient resiliency to flex when the valve is pressed against its seat and to maintain the valve tightly seated notwithstanding lost motion in the linkage and notwithstanding heavy vibration. By using a bowed resilient rod in the control linkage the 80 steam valve is maintained tightly seated without adding any parts, the bowed rod taking the place of the usual reach-rod. The bowed rod 14 also serves to take up the 85 lost motion of the control linkage when the valve is open in the following manner. In fully opening the steam valve the handle C_s is pulled over until the valve 1 seats upwardly against face 25 and until the bowed rod 14 is sufficiently stretched or straightened 90 from normal curvature to hold the train of linkage tight.

The operation of the system is as follows: To set the injector in action the final overflow valve V_o'' is opened, the water valve 95 V_w is opened (the lower valve 8 opening with the upper valve 10 due to the pressure of the water therebelow), and the steam valve V_s is lifted sufficiently to open the upper valve 1 but not the lower valve 3. Steam 100 then flows past valve 1, through passage 19, and thence through lifter nozzle LN to the lifter tube LT; and water is thereby caused to flow past valve 8—10, through passage 20, lifter tube LT, passage 21, thence 105 through the force tube FT and the intermediate overflow valve V_o' in parallel, the valve V_o' being automatically lifted by the pressure of the water, and thence to the final overflow V_o'' . After the flow of water 110 is thus established the steam valve V_s is further lifted until the lower valve 3 is opened, whereupon the flow of water is maintained by steam flowing through force nozzle FN. The final overflow valve V_o'' 115 is then closed and the water flows through the delivery passage D to the boiler, the intermediate overflow valve V_o' being automatically closed and the check valve V_c being automatically opened by the pressure 120 of the water in the chamber surrounding the force tube FT. After the injector has thus been set in action the rate of flow may be controlled merely by raising or lowering the steam valve V_s . 125

In cold weather when the injector is idle the water in advance of the water valve, i. e. the water in the pipe or hose leading to the injector and if desired also the water in the tender, may be heated in the following man- 130

ner to prevent freezing. The steam control lever C₈ is advanced one notch thereby permitting the bowed link 14 to assume normal shape and then raising upper valve 1 5 a small distance but not far enough to withdraw piston 22 from the opening in valve seat 2, whereby steam is permitted to flow through valve 1 around piston 22 in small measure. The water valve handle C_w is 10 then moved into open position, thereby raising upper valve 10. Lower valve 8 does not follow the upper valve for the reason that the steam pressure above the valve exceeds the water pressure below. The openings 13 15 are thereby uncovered permitting the steam to flow through valve 8 to heat the water.

By virtue of the construction of the steam valve and its control mechanism this valve is opened only a slight amount upon the 20 movement of the control handle one full notch. This permits steam to flow in small measure at a pressure sufficient to hold down valve 8 and warm the water in advance of the water valve but insufficient to actuate 25 the annunciator or tell-tale T. By virtue of the construction of the water valve and its control mechanism both parts open together to supply water to the injector but only the upper part opens to supply heating 30 steam to the feed water, the action of the lower valve being automatic. And by virtue of the coördination of the steam and water valves, these valves function either to control the flow of water to the boiler 35 or to control the flow of steam to the feed water, the valves being actuated by the same levers and in the same directions in each case. The unique arrangement of valves and control mechanism also makes it possible to throttle the flow of water solely by 40 the steam valve, the valve commonly employed at the lifter nozzle being rendered wholly unnecessary and therefore being eliminated.

45 The opening of the steam valve such a small amount as to permit steam to flow in sufficiently small measure not to actuate the tell-tale annunciator is rendered possible by the piston 22 telescoping into valve seat 2.

50 I claim:

1. An injector device comprising a steam valve, a seat therefor, means for lifting said valve from its seat to a predetermined amount, and means for permitting the passage of steam in minute quantities only through said valve when so raised.

2. An injector device comprising a steam valve, an annular valve seat having a steam passage therethrough, means for lifting said valve from its seat, and means for obstructing the free flow of steam through said passage during the first stages of opening movement of the valve.

3. An injector device comprising a steam 65 valve, an annular seat therefor providing

a cylindrical steam passage, and a cylindrical piston member secured to said valve and normally extending into and loosely fitting within said passage.

4. An injector device comprising a double steam valve having upper and lower valve members, an annular seat for the upper valve member providing a cylindrical steam passage, a cylindrical piston secured to said upper valve member and extending 70 into and loosely fitting within said passage, a spider extending downwardly from said piston, and means carried by said spider for supporting the lower valve member.

5. An injector device having steam and 80 water inlet passages, a valve for controlling said steam inlet passage, a lever for actuating said valve, and a notched locking sector for said lever, said valve comprising an extension member so constructed and arranged that upon moving said lever into engagement with the first notch of said sector, steam will be permitted to bleed past 85 said extension member in predetermined minute quantities.

6. An injector device having a water inlet passage, an annular valve seat defining such passage, a manually closable main valve member coöperable with said seat for obstructing the flow of water therethrough, 90 said valve member having an opening therethrough, and means engageable with said valve member for controlling the passage of water through said opening.

7. An injector device having a water inlet passage, an annular valve seat surrounding the same, a reciprocable main valve member coöperable with said seat, said valve member having an opening therethrough and being constructed and arranged to be 100 lifted from said seat by the pressure of water within the inlet passage, and manually actuatable means operable to close said opening in the main valve and to hold the latter against its seat.

8. An injector device comprising a water inlet valve having a main valve member engageable with a valve seat, said valve member having a guide stem secured thereto, and means for forcing said main valve to its seat 115 comprising a rotatable member having a socket for engagement with said guide stem.

9. An injector device comprising a water inlet valve having a valve seat, a main valve coöperating therewith, said valve having an 120 opening therein, a guide stem projecting from said valve, a secondary valve for closing said opening and having a socket for loosely receiving said guide stem, and manually controllable means for actuating said secondary valve.

10. An injector device having steam and water controlling means, said latter means comprising an annular valve seat, a main valve disk coöperating therewith, said disk 130

having a series of openings therethrough surrounding an upstanding guide stud, a secondary valve member having a socket loosely engaging said stud and a flange for covering said openings, said valve member being externally screw threaded for engagement with an internally threaded holder, and means for rotating said member relatively to its holder.

10. 11. An injector apparatus comprising steam and water inlet valves, said water inlet valve comprising a plurality of members movable simultaneously in the same direction for admitting water, and means for 15 moving one of said members independently of the other to permit the passage of steam therethrough.

12. An injector apparatus comprising a steam inlet passage, a water inlet passage, 20 valves for controlling the flow of steam and water through the respective passages, and a lifter nozzle having a free and unobstructed and constantly open entrance.

13. An injector apparatus comprising 25 steam and water controlling valves, an actuating lever for said steam valve, means for locking said lever in adjusted position, and connections between said lever and the steam valve comprising a reach rod having 30 an interposed flexible portion of laterally bowed form.

14. In a boiler feeding injector, the com-

bination with a system of steam and water control, of a steam supply closure valve and linkage for actuating same, and a stop arranged to engage said valve when open, said linkage including a bowed flexible rod adapted to maintain said linkage tight when the valve is either opened or closed.

15. An injector device comprising a steam 40 inlet valve, lifter and force nozzles, a pressure controlled water inlet valve, a telltale, and lever means for controlling said inlet valve, said steam inlet valve being so constructed and arranged that a predetermined 45 movement of said lever means serves to admit steam to the injector in sufficient amount to hold said water inlet valve upon its seat but in insufficient amount to actuate the telltale.

16. An injector device comprising a steam inlet valve, a manually operable lever for actuating same, lifter and force nozzles, a telltale, and a pressure operated water inlet valve comprising a disk having perforations 55 therein, said steam valve being so constructed and arranged that upon a definite movement of the lever, steam will be admitted for warming the water in the supply pipe but in insufficient quantity to actuate the 60 telltale.

Signed by me at Boston, Massachusetts, this 5th day of August, 1919.

BELVIN T. WILLISTON.
